PLURAL TRANSMITTER TELEGRAPH SYSTEM WITH NUMBER TRANSMITTER

Reginald G. Schuler, Highland Park, Ill., assignor to Teletype Corporation, Chicago, Ill., a corporation of Delaware

Application January 23, 1946, Serial No. 642,916

9 Claims. (Cl. 178—3)

1

The present invention relates to telegraph transmission stations, and more particularly to an automatic telegraph transmission station.

In present day transmission centers handling a large number of messages, it often occurs that certain of the messages to be transmitted have a priority or are rush messages and thus should receive preference with respect to the normal or regular messages handled which make up the greater portion of the total of work handled. In order that such priority messages be handled with the greatest expediency it is desirable that automatic means be provided to control transmission thereof.

Accordingly, an object of the present invention is to provide automatic means whereby priority messages may be transmitted in preference to regular messages.

It is manifest, however, that such an automatic system should operate in such a manner that the transmission of a regular message will not be broken into for transmission of a priority message. Likewise, priority message transmission should not be broken into by regular message transmission.

Accordingly, another object of the invention is to provide means so that automatic transmission of priority messages will not break in during transmission of a regular message but will be transmitted immediately after the complete transmission of the regular message and also so that priority message transmission will not be interrupted by regular message transmission.

Because of the great numbers of messages handled daily by transmission centers it has become desirable, and almost necessary, to provide automatic numbering apparatus for designating each message transmitted by an identifying number. Such number may precede or follow each message text, depending on the particular scheme of transmission utilized.

Accordingly, still another object of the invention is to provide means to cause the automatic operation of message numbering apparatus to transmit an identifying number for each message, whether it be in the priority or regular category.

In general, the invention provides for a plurality of regular message transmitters, a plurality of priority message transmitters, and a numbering transmitter, operating automatically in such a manner that an identifying number will be transmitted for each message transmitted through the operation of the numbering transmitter, the priority message transmitters will be 55

2

operated in which messages are available, and finally the operation will occur of regular message transmitters in which messages are available. In the event that no messages are initially available in priority transmitters the regular message transmitters will be operated in which messages are available, each being accompanied by an identifying number, until such time as a priority message is available which will then be transmitted, but only after the preceding regular message is completed.

The invention may be better understood by reference to the accompanying drawing illustrating such a message center or transmission station including suitable apparatus, when viewed in conjunction with the following detailed description of the apparatus and its operation.

For the sake of clarity the following description will first describe the operation of the regular message transmitters in conjunction with the message numbering transmitter. Thereafter, the description will describe the operation of the station when messages are available in the priority message transmitters in conjunction with the message numbering transmitter, and also in conjunction with the regular message transmitters. The latter description will include the situation of a regular message transmitter operating and a message being available in a priority message transmitter, whereby the latter is precluded from operation until the regular message is completely transmitted and the next identifying number has been sent.

The instant apparatus provides for each identifying number to be transmitted preceding the message which it identifies.

The transmission station is provided with a plurality of tape transmitters which may be similar to the type disclosed in Bulletin No. 141, 40 published by the Teletype Corporation, Chicago, Illinois, in March, 1942, only two of which are shown and designated by the numerals 11 and 12. Such transmitters may be termed the regular message transmitters, inasmuch as the normal or regular messages, as distinguished from a rush or priority message, will be transmitted from these units. Each of the regular message transmitters such as 12 is provided with a distributor 13 for transmitting the message signals, a release magnet 14 for allowing the distributor to commence operation, and a tape indicator indicated generally as 16 which operates under the control of message tape within the transmitter in a manner which will be described more fully hereinafter.

The transmission station also comprises a plurality of rush or priority message transmitters only two of which are shown, indicated generally by the numerals 17 and 18. The priority message transmitters are similar to those described above, each having a distributor 19, a release magnet 21 for the control thereof, and a tape indicator indicated generally by the numeral 22. The tape indicator 22 differs from the tape indicator 16, previously described, in a manner which will be described more fully hereinafter.

With respect to the tape indicator 16 associated with the regular message transmitter 12, the same comprises a contact member 24 which is movable toward the right to engagement with a contact point 26 when tape is available in the transmitter and which is movable toward the left in engagement with an associated contact point 27 when no tape is in the transmitter, or when an end-of-message signal is sensed in the tape under the control of a special end-of-message feeler, which is well known in the art.

A stepping switch indicated generally by the numeral 28 is provided for the regular message transmitters and in the instant example is shown as comprising four contact banks 30 to 33, inclusive. Each of the contact banks 30 to 33, inclusive, has associated therewith an individual wiper which is caused to step to successive contact points under the control of a stepping magnet 34 in a well known manner and as will be described more fully hereinafter.

It may be seen by reference to the drawing and particularly with respect to regular message transmitter 12 that the distributor 13 is connected by means of a conductor 36 to the first contact bank 30. The distributor start magnet 14 is connected by a conductor 37 to the second contact bank 31. The right-hand contact 26 of the tape indicator device 16 is connected by a conductor 38 to the third contact bank 32 whereas the left-hand contact 27 of the tape indicator 16 is connected by a conductor 39 to the fourth contact bank 33.

By reference to the drawing it may be seen that each transmitter such as 12 is connected to a single set of contact points of the contact banks 30 to 33, inclusive, in such a manner that when the individual wipers are stepped to any similar set of contact points, such as the first set for instance, the transmitter 12 will be connected in the manner described above.

The regular transmitter 11 would be connected similarly in all its parts to the second contact points, for instance, of the banks 30 to 33, inclusive, and further transmitters would be connected in a similar manner to others of the contact points. Only two transmitters have been illustrated and connections for only one shown in order to disclose the apparatus as simply as possible. It is to be understood, however, that the operation of the apparatus described hereinafter would be similar for any of a plurality of transmitters.

By referring now to the stepping magnet 34 for controlling the stepping switch 28 it may be seen that such may become energized over a circuit which may be traced from grounded battery 41, through a resistor, through an armature 42 of a relay 43, over a conductor 44, through an armature 46 of the stepping magnet 34, and through the winding of the magnet 34 to ground. The magnet 34 will, therefore, become energized causing the individual wipers of the selector switch 28 to be moved simultaneously to successive

contact points. Such occurs because every time the stepping magnet 34 becomes energized, it attracts its associated armature 46 thereto, thus breaking the stepping circuit just described and causing the stepping magnet 34 to be de-energized. Upon de-energization of this magnet its armature 46 falls back to its original or right-hand position thereby again completing the circuit for the energization of the magnet 34, resulting in the wipers being moved another step or to the next succeeding set of contact points of the banks 30 to 33, inclusive. If an assumption is made that a tape is available in the regular message transmitter 12, resulting in the movable contact 24 being in engagement with the right-hand contact 26, as previously described, a circuit will be established from grounded battery 41, through the swinger 24 and contact 26, over the conductor 38 to the first contact point of the contact bank 32, through the individual wiper of that contact bank, over a conductor 48 to junction point 49, over a conductor 51 and through the winding of the relay 43 to ground. The relay 43 thus becomes energized attracting its armature 42 thereto and thus precluding further establishment of the electrical circuit previously described for the energization of the stepping magnet 34. The stepping magnet 34, therefore, no longer can be energized and the wipers will not be advanced further but will remain on the first contact point of the banks 30 to 33, inclusive.

The circuit described immediately above may also be traced from junction point 49 over a conductor 52, through the winding of a relay 53, over a conductor 54, and through an armature 56 of a relay 57 to ground. The relay 53 will thus become energized resulting in its armatures 58 and 59 being attracted thereto. It might be noted at this point that the relays 43 and 53 will remain energized as long as there is tape in the tape indicator 16 inasmuch as battery 41 may then be applied continuously to the movable swinger 24 and the contact 26 for establishing the circuits traced.

It may be seen that under the normal or de-energized condition of the relay 53 the armature 59 will be in its right-hand position whereat a circuit is established from grounded battery 61, through the armature 59, and through a condenser 62 to ground. The result of such circuit is that the condenser 62 will become charged from the battery 61 in which condition it will remain until the relay 53 is energized causing the armature 59 to be attracted thereto and moved to engagement with its left-hand contact point, at which time the condenser 62 will discharge, as will be described.

Upon the armature 59 moving to its left-hand contact point, a circuit will be established for the discharge of the condenser 62 which may be traced from ground, through the condenser 62, over the armature 59, over a conductor 63 to junction point 64, over a conductor 66, and through the winding of a relay 67 to ground. The relay 67 will immediately energize due to the discharge of the condenser 62.

A single numbering transmitter 68 is provided at the transmission station which is very similar to the previously described transmitters in that it has a distributor 69 for signal impulses, a release magnet 71 for controlling the operation of the distributor, and a special tape indicator, shown generally as 12, which comprises a movable swinger 73 and a contact point 74 which are

normally closed but which are opened upon the sensing of a particular signal in the numbering tape in the transmitter 68, which may be, for instance, a "letters" combination. The tape indicator 72 may also operate in response to the sensing of a special end-of-message signal in the tape.

It is contemplated that the numbering transmitter 68 will utilize a loop of tape which has been prepared with coded perforations of successive numbers therein. Each number code combination will be followed by a special code perforation indicative of a "letters" combination or by a special end-of-message signal such as a sixth perforation, so that successive numbers will be separated and for a purpose which will be described more fully hereinafter.

Upon the energization of the relay 67, due to the discharge of the condenser 62, a locking circuit for the relay is established which may be traced from ground, through the winding of the relay 67, through the armature 76 which is associated therewith and which is attracted upon the energization of the relay, over a conductor 71, through the movable swinger 73 of the tape indicator 72 at the numbering transmitter 68, and through the contact 74 with which it is in engagement, to grounded battery 78. As was previously mentioned, the swinger 73 is normally in engagement with contact 74 and thus the locking circuit for the relay 67 will remain as such until a "letters" or other special combination is sensed in the numbering tape to cause the swinger 73 to move away from the contact 74. It might be again mentioned that such combination which was mentioned as being a "letters" combination is perforated in the tape only after the perforations indicative of the particular number, and, therefore, the contact will remain closed until the number has been transmitted and the "letters" combination sensed.

It is necessary for the locking battery just described to be applied to the relay 67 because even though the relay 53 remains energized there will be no more potential from the condenser 62 after it has discharged to cause the relay 67 to remain energized.

It should also be noted that upon the energization of the relay 53, the armature 58 is attracted thereto, which normally would result in an electrical circuit being established which may be traced from ground, through the winding of the distributor release magnet 14 of the regular message transmitter 12, over the conductor 37, through the first contact of the bank 31, through the wiper in engagement therewith, over a conductor 79, through the armature 58 now in its right-hand position, over a conductor 81, and through an armature 82 normally in its left-hand position, to grounded battery 83. However, upon the discharge of the condenser 62, the relay 67 will operate very rapidly in such a manner that it will attract its associated armatures, one of which is the armature 82, prior to the energization of the start magnet 14. Thus, inasmuch as the energizing circuit of the start magnet 14 is traced through the armature 82 it is impossible for the start magnet 14 to be energized at this time.

Upon the energization of the relay 67 its armature 84 will also be attracted thereto which results in the latter engaging and closing a contact 86 and causing a contact pair 87, which was previously closed, to be opened.

At the same time and upon the attraction of

the armature 88, an electrical circuit is established which may be traced from grounded battery 89, through the armature 88 which is now in its right-hand position, over a conductor 91, through the coil of the distributor release magnet 71 of the numbering transmitter 68, to ground. The distributor release magnet 71 will thus become energized resulting in the distributor 69 being released for operation in a manner well known in the start-stop telegraphy art.

The numbering transmitter 68 will operate to sense the codal combinations in its tape in a well known manner and results in their being transmitted over a circuit which may be traced from grounded battery 92, through the distributor 69, over a conductor 93, through the armature 84, through the contact 86 with which it is in engagement, and over the line conductor 94 to a distant station whereat ground is supplied. The transmitter 68 will operate to sense the tape and cause the transmission of any predetermined identifying member, which is utilized to precede and identify the intelligence message from the regular message transmitter 12.

Upon the completion of the identifying number being transmitted from the transmitter 68, a predetermined codal combination will be sensed in the tape thereat, described previously as a "letters" combination or an end-of-message signal, causing the movable swinger 73 to move toward the left out of engagement with its associated contact 74. As a result of the opening of such contact the locking circuit which was previously described for causing the relay 67 to remain energized will be broken and the relay 67 will de-energize, causing its armature 84, 76, 88, and 82 to no longer remain attracted but instead to drop away.

As a result of the dropping away of the armature 88 the circuit previously traced for the energization of the distributor release magnet 71 of the numbering transmitter 68 will no longer be established and the magnet 71 will become de-energized.

As a result of the nonattraction of the armature 84 the latter will fall away from engagement with its contact 86 and allow the contact pair 87 to once again become closed. This has the effect of removing the distributor 69 of the numbering transmitter 68 from connection to the line conductor 94.

Upon the nonattraction of the armature 82, the electrical circuit previously described from grounded battery 83, through the armature 82, over the conductor 81, through the armature 58, over the conductor 79, through the contact bank 31, over the conductor 37, and through the coil of the distributor release magnet 14 of the regular transmitter 12 to ground, will be established, resulting in the magnet 14 becoming energized thus releasing the distributor 13 for operation.

The nonattraction of the armature 83 to engagement with its left-hand contact point will have no effect at this time inasmuch as the circuit traceable through the armature 96 of the relay 57 will not be completed due to the non-energization at this time of the relay 57, thus positioning the armature 96 in its unattracted position away from its associated contact.

Upon the release of the distributor 13 of the regular message transmitter 12, as just described, a circuit is established which may be traced from grounded battery 97, through the distributor 13, over the conductor 36, through the contact bank 30, over a conductor 98, through a closed contact

pair 99, over a conductor 101, through the contact pair 81, now closed, and over the line conductor 94 to the distant station whereat ground will be supplied. The regular message transmitter 12 will continue to operate with the sensing mechanism thereat sensing the various codal combinations in the tape and causing signals to be transmitted by means of the distributor 13 over the line conductor 94. The transmitter will thus continue to operate until the entire message has been transmitted at which time the tape will no longer be in the transmitter or the transmitter will sense a special end-of-message signal which will result in the operation of the tape indicator 16 in such a manner as to cause the movable member 24 to be removed from engagement with the right-hand contact 26 and instead be positioned in engagement with the left-hand contact 27.

As a result of the swinger 24 moving from its right-hand contact 26 to its left-hand contact 27, the circuit which had previously been traced through the contact 26, over the conductor 38, through the contact bank 32, over the conductor 48 to junction point 49, through the conductor 51 and the winding of relay 43 to ground will be broken, thus resulting in the de-energization of the relay 43. As a result of this the armature 42 will no longer be held attracted but instead will be allowed to move to its left-hand or unattracted position, once again establishing the circuit for the switch stepping magnet 34, the operation of which has previously been fully described. The operation of the stepping magnet 34 will cause the wipers of the stepping switch 28 to be moved to consecutive contact points until such time as a point is reached at which the tape indicator 16 of a regular message transmitter is so set that the movable member is in engagement with its right-hand contact point at which time a circuit will once again be established through the contact bank 32 for the energization of the relay 43, thus once again precluding operation of the stepping magnet 34. This will occur for the next regular message transmitter having tape available.

At the same time that the relay 43 de-energizes, the relay 53 will likewise de-energize inasmuch as no potential is received from the junction point 49 and over the conductor 52. Upon the de-energization of the relay 53 its armatures 58 and 59 will move to their unattracted positions.

The movement of the armature 58 to its unattracted position results in the electrical circuit being broken which was previously described as resulting in the energization of the distributor release magnet 14 of the regular message transmitter 12. Thus the distributor 13 will no longer operate and the regular message transmitter 12 will be precluded at this time from further transmitting.

Likewise, upon the de-energization of the relay 53 and the falling away of its armature 59 the latter will move to its right-hand position at which time a circuit is established from the grounded battery 61, through the armature and to the grounded condenser 62. The condenser 62 thus again charges in readiness for the next time that the relay 53 is energized, at which time the armature 59 will be moved toward the left and the discharge of the condenser 62 will once again result in the energization of the relay 67, all as previously described.

It should be noted that the stepping magnet 34 will operate to step the wipers of the stepping

switch 28 to successive contact points until a position is reached whereat one of the plurality of the regular message transmitters, such as 11 or 12, is found with tape available for transmission.

- 5 At this time operation will occur similarly to that described above and the selected transmitter will operate to cause an identifying member to be transmitted from the numbering transmitter 68 and then the operation of the message transmitter to transmit the regular message over the line conductor 94. It is obvious that if another tape is made available in the message transmitter 12 it will again operate, similarly to the manner just described, at such time as the stepping switch 28 is progressed sufficiently for the wipers to be once again on the first contact points.

It is to be remembered that the present invention incorporates means whereby if rush or priority messages are available they will be transmitted in preference to regular or standard messages, the transmission of which has just been described. Therefore, the operation of the rush or priority transmitters will now be described in conjunction with the numbering and regular message transmitters.

- 20 It is to be remembered that the rush or priority transmitters such as 17 and 18 were described as comprising a distributor 19, a distributor release magnet 21, and a tape indicator 22, all of which are very similar to the corresponding elements described with respect to the regular message transmitters. It should be noted, however, that the tape indicator 22 of the priority message transmitter 17 is provided with two movable swingers 102 and 103 which operate together and which cooperate with contact points 104 and 106, respectively, in such a manner that the swingers will be in engagement with their associated contacts when the tape indicator 22 is in a rightward position indicating that tape is available in the tape transmitter.

Associated with the priority message transmitters is a stepping switch indicated generally by the numeral 107 which comprises three contact banks 108, 109, and 111, each having individual wipers associated therewith. The stepping switch 107 operates similarly to the stepping switch 28, previously described, under the control of a stepping magnet 112 in a manner which will be described more fully hereinafter.

- 30 55 The distributor 19 of the priority message transmitter 17 is connected over a conductor 113 to the contact bank 103, the distributor release magnet 21 is connected over a conductor 114 to the switch bank 109, and the contact 106 associated with the movable swinger 103 is connected over a conductor 116 to the switch bank 111.

The contact 104 associated with the movable member 102 is connected over a conductor 117 to the winding of a relay 118.

- 60 65 It is to be remembered that in the description of the operation of the regular message transmitters the stepping switch 28 associated therewith was previously stepped under the control of a stepping magnet 34 until such time as a transmitter was connected having tape available therein. In respect to the instant or rush message transmitters, the stepping switch 107 is not operated under the control of the stepping magnet 112 until such time as tape is available in one of the priority transmitters. At such time the tape indicator 22 will be positioned toward the right with the movable swinger 102 in engagement with the contact 104, thus completing a circuit from ground, through the swinger 102,

through the contact 104, over the conductor 117, through the winding of the relay 118, to grounded battery 119. The relay 118 thus becomes energized in which condition it will remain until such time as the tape indicator 22 moves to the left signifying that the message has been sent or that there is no tape available in any priority transmitter.

Upon the energization of the relay 118 its armature 121 will be attracted thereto, resulting in the completion of an electrical circuit which may be traced from grounded battery 122, through the unattracted armature 123 of a relay 124, over a conductor 126, through the armature 121, previously mentioned as being in its attracted position, over a conductor 127, through the winding of the magnet 112, through the armature 128 of the stepping magnet 112, to ground. The stepping magnet 112 thus becomes alternately energized and de-energized and causes the wipers of the stepping switch 107 to be successively stepped until such time as the tape transmitter having the tape available therein, such as 17 for example, is connected to the three contact banks of the stepping switch 107. Such successive stepping through the operation of the stepping magnet 112 results, inasmuch as every time the stepping magnet 112 becomes energized it attracts its armature 128 thereto resulting in the breaking of the electrical circuit which has just been described for the energization of the stepping magnet. Upon the attraction of the armature 128 the stepping magnet 112 de-energizes, the armature 128 falls back to its unattracted position and the stepping magnet 112 once again becomes energized to repeat the conditions just described. Thus, the stepping switch 107 will be operated successively as described, but, as also described, only when there is a rush message tape available in one of the priority message transmitters.

At such time as the stepping switch 107 positions its associated wipers on the contact banks in such a manner as to connect the first priority message transmitter having tape available therein as evidenced by the swingers 102 and 103 being moved to the right, an electrical circuit will be established which may be traced from ground, through the movable swinger 103, through the contact 106 in which it is in engagement, over the conductor 116, through contact point and wiper of the contact bank 111, over conductor 129 to junction point 131, over conductor 132 and through the winding of a relay 124 to grounded battery 133. Upon the establishment of such circuit the relay 124 becomes energized and attracts its armature 123 thereto which results in the breaking of the circuit previously described for causing the energization of the stepping magnet 112. Thus, at this time the stepping magnet 112 will no longer be able to become energized, and, therefore, will not step the stepping switch 107 to any further contact point until such time as the tape indicator 22 is positioned to its left to indicate the message has been sent or that no tape is available.

At the same time as just described above, another electrical circuit may be traced from the junction point 131, over a conductor 134, through the winding of the relay 57, over a conductor 136 to junction point 137, over a conductor 138, through the contact bank 33 of the stepping switch 28, over the conductor 39 to the contact point 27, and through the movable swinger 24 to grounded battery 41. It should be remembered at this time that the movable swinger 24 is toward

the left in engagement with the contact 27 inasmuch as the tape indicator 16 has been operated to indicate that there is no tape available in the regular message transmitter 12 or that the end-of-message signal has been sensed. The result of the establishment of such a circuit is the energization of the relay 57 which results in the attraction of its armatures 56, 96, 139, 141, and 142.

It should be noted that the stepping switches 10 28 and 107 operate independently of each other and therefore during the operation of one of the regular message transmitters, such as transmitter 12, the stepping switch 107 will operate to connect the rush message transmitter having tape available thereat to the contact banks 108, 109, and 111. In this manner it is assured that as soon as the regular message is transmitted and the tape indicator 16 moved to the left the circuit is established for the energization of the relay 57, even though the remaining regular message transmitters may have message tape available thereat.

As the armature 139 is attracted a circuit is established which may be traced from grounded battery 143, through the armature 139, over a conductor 144 to junction point 137, and thence over conductor 136 and through the winding of the relay 57 and over the circuit previously described to the tape indicator 22. This acts as 25 locking battery for the relay 57 and allows the relay to remain energized even though someone may restore the tape to the regular message transmitter 12 resulting in the movable swinger 24 being moved from contact 27 to contact 26, or 30 though the stepping switch 28 may be advanced to connect another message transmitter having tape available to the contact bank 33.

When the armature 141 is in its normal or unattracted position an electrical circuit is completed from grounded battery 146, through the armature 141 and through a condenser 147 to ground. During the unenergized condition of 40 relay 57 the condenser 147 will build up a charge from battery 146 which upon the relay 57 energizing and attracting its armature 141, thereto, results in potential being discharged over a conductor 148 to junction point 64 and thence over the conductor 66 and through the winding of 45 relay 67 to ground. Relay 67 will immediately 50 energize.

Upon the energization of the relay 57 its armature 56 is also attracted thereto which results in the breaking of the circuit from ground, through armature 56, and over conductor 54 to 55 the winding of the relay 53. Under this condition the relay 53 can not become energized and, therefore, the regular message transmitters such as 12 will not be able to operate or transmit message intelligence over the line conductor 94.

60 The energization of the relay 57 also results in its armature 96 being attracted thereto which would normally result in the completion of a circuit from grounded battery 89, through the armature 88, over a conductor 149, through the armature 96, over a conductor 151, through the contact bank 109, over a conductor 114, and through the winding of distributor release magnet 21 to ground. However, such circuit is not established because as a result of the rapid discharge of the condenser 147 and the subsequent rapid energization of the relay 67, its armature 88 will be attracted thereto prior to the energization of the distributor release magnet 21 which precludes the supplying of potential for 70 the energization of that magnet from the battery 75

11

88 until such time as the armature 88 returns to its unattracted position due to the de-energization of the relay 67.

The energization of the relay 57 causes the attraction of its associated armature 142 and places that armature in engagement with an associated contact 152 and causes the opening of the contact pair 99, previously mentioned.

Upon the energization of the relay 67 through the discharge of the condenser 147 its armature 76 is attracted thereto which results in locking battery being supplied from the grounded battery 78 at the numbering transmitter 68, through the tape indicator 12 in a manner which was previously described for the supplying of locking battery for this same relay in the description of the operation of the regular message transmitter.

The movement of the armature 88 of the relay 67 rightwardly not only precludes the completion of an electrical circuit for the energization of the distributor release magnet 21 of the rush transmitter 17 but upon its movement to the right completes a circuit from grounded battery 89, through the armature 88, over the conductor 91, and through the winding of the distributor release magnet 71 at the numbering transmitter 68 to ground. The distributor 69 of the numbering transmitter 68 will thus be released for operation resulting in the message identifying number being transmitted over a circuit from grounded battery 92, through the distributor 69, over the conductor 93, through the armature 84 which is in its left-hand position due to the energization of the relay 67, through contact 86 and over the line conductor 94 to the distant station. After the identification number has been transmitted, the tape indicator 72 of the numbering transmitter will operate similarly to that described previously, resulting in, upon the sensing of a "letters" combination or an end-of-message combination, the movable member 73 being removed from engagement with its contact 74. This latter condition results in locking battery previously traced from battery 78 no longer being applied to the relay 67, thus resulting in the de-energization thereof.

Under this condition the armature 84 will no longer be attracted to its leftward position in engagement with the contact 86 but will be opened thereat resulting in the message numbering transmitter 68 no longer being connected to the line conductor 94 but instead allowing the closure of the contact pair 87.

At this time also the armature 88 will once again move to its unattracted position resulting in the establishment of an electrical circuit from battery 89 through the winding of the distributor release magnet 21 of the priority message transmitter 17, as previously traced. The energization of this magnet causes the release of the distributor 19 which results in the transmission of the rush message over the line conductor by means of a circuit which may be traced from grounded battery 153, through the distributor 19, over the conductor 113, through the contact bank 108, over a conductor 154, through the armature 142 which is in engagement with the contact 152 due to the energization of the relay 57, over the conductor 101, through the closed contact pair 87, and over the line conductor 94 to ground which is supplied at the distant station.

The priority message transmitter 17 will thus continue to operate to transmit its complete message over the line conductor 94 in a manner well known in the telegraphic art.

12

At the completion of the transmission of the rush message, the tape will no longer be available in the tape transmitter 17 or an end-of-message signal will be sensed therein resulting in the tape indicator 22 moving to its left-hand position which is the normal position with no tape available for message transmission. Upon this occurrence, the movable member 102 will no longer engage the contact 104 and thus ground will no longer be supplied over conductor 117 for the energization of the relay 118. At this time the relay 118 will de-energize causing its armature 121 to fall away therefrom thus breaking the circuit which was previously described for the energizing circuit of the stepping magnet 112. Thus, the stepping magnet will not be able to step the stepping switch 107 to a new position unless a tape should be in one of the other priority transmitters such as 18 which would, of course, result in a completed stepping magnet circuit.

At the same time, the movable member 103 is removed from engagement with the contact 106 thus removing ground from conductor 116 through switch bank 111, conductors 129 and 132, and through the coil of the relay 124. Relay 124, therefore, de-energizes resulting in its armature 123 moving to its right-hand position thus preparing the circuit for the stepping magnet 112 for energization upon the attraction of the armature 121 as a result of the closure of the tape indicator 22. At the same time ground is also removed from the circuit extending from junction point 131, over conductor 134, through the winding of relay 57, over conductor 136 to junction point 137, over conductor 144, and through armature 139 to grounded battery 143. Relay 57, therefore, de-energizes resulting in the armatures 139, 56, 96, 141 and 142 all moving to their unattracted positions.

Upon armature 142 becoming unattracted it is removed from engagement with its contact 152 thus removing the distributor 19 from connection with the line conductor 94 and instead allowing the contact pair 99 to close.

The falling away of armature 141 allows the circuit for charging the condenser 147 to be again established, the condenser storing potential until such time as the circuit may be broken again by the attraction of armature 141.

The falling away of the armature 96 results in the circuit being broken which previously was traced for the energization of the distributor release magnet 21, thereby precluding further operation of the transmitter 19 of the rush or priority message transmitter 17.

Also upon de-energization of the relay 57 the armature 56 moves to its unattracted position thereby conditioning a circuit for the energization of relay 53 which occurs in the event that there is tape in any of the regular message transmitters and no tape available in any of the priority message transmitters.

The falling away of armature 139 breaks the locking circuit for the relay 57 which it was described is utilized in the event that after the priority message transmitter has been conditioned tape is replaced in the regular message transmitter 13 thus causing the movable member 24 of the tape indicator 16 to be placed in engagement with its contact 26.

As a result of the above occurrences the apparatus is now conditioned for retransmission depending on whether messages are available in the priority or regular message transmitters. In the event that the former is true the priority

message transmitter having the message therein will be conditioned which will result in the numbering transmitter first transmitting the message identifying number and thereafter the priority message being transmitted over the line conductor, all in a manner as described. If no messages are available in any of the priority message transmitters, the regular message transmitter having tape available therein will operate, first being conditioned and causing the transmission of the identifying number through operation of the numbering transmitter 68 and thereafter sending the regular message stored in its tape. The transmission station will thus operate as described above continuously as long as there are messages available in tape form in any of the transmitters, either regular or priority.

It was previously mentioned that a condition could occur wherein one of the regular message transmitters was transmitting a message and tape was made available in one of the priority message transmitters. Obviously under this condition it is undesirable to break in on the message being transmitted but instead desirable to transmit the priority message upon completion of the regular message. The above possible difficulty is overcome by making it necessary to trace the circuit for the energization of the relay 57 which controls the operation of the priority transmitters through the switch bank 33 of the stepping switch 28 and the tape indicator 16 of the regular message transmitter 12. That is, at such time as the regular message transmitter 12 is transmitting its message the tape indicator 16 will be positioned with its movable swinger 24 in engagement with the right-hand contact 26 and thus no battery is available through the contact 27 for causing the energization of the relay 57. However, immediately upon the completion of the message the movable swinger 24 will move to the left thus supplying battery for the energization of the relay 57 conditioned through the tape indicator 22 of the priority transmitter being in its right-hand position thereby allowing operation of the priority transmitter having tape available therein and precluding operation of any of the regular message transmitters through preventing energization of the relay 53 at armature 56. Therefore, the regular message transmitters are also precluded from operating during the operation of any of the priority message transmitters.

It is obvious that even though tape were available in one of the other regular message transmitters such as 11, the priority transmitter 11 would still operate as described above because no circuit could be traced through the bank 32 for the energization of the relay 53 prior to the disabling of that relay inasmuch as the wiper of switch bank 32 would remain on the contact point associated with the regular message transmitter which had just transmitted its message a sufficient time to allow operation of the relay 57.

In view of the above description it is obvious that the transmission station will operate to transmit regular type messages and priority or rush type messages, every one of which is preceded by an identifying number. Likewise, through automatic operation of the system the priority messages will be transmitted in preference to the regular messages but will not break in during number transmission or transmission of any of the regular messages.

It should also be noted that the transmitting station may be operated in a reverse manner; that is, the selector switch 107 could operate con-

tinuously whereas the selector switch 28 would operate only when tape is in one of the regular transmitters.

It is obvious that the above description is of a specific embodiment of the invention and that such is but illustrative only, the invention not being limited to the particular disclosure.

What is claimed is:

1. In a telegraph transmission station, a plurality of rush message transmitters, a plurality of regular message transmitters, means associated with said rush message transmitters and under the control thereof for selecting a rush message transmitter having a message available thereat, means associated with said regular message transmitters for selecting a regular message transmitter having a message available thereat, and means under the control of said rush message transmitters to give them preference of transmission over said regular message transmitters.

2. In a telegraph transmission station, a plurality of rush message transmitters, a plurality of regular message transmitters, a tape indicator in each of said rush message transmitters for determining the availability of rush message tape, a tape indicator in each of said regular message transmitters for determining the availability of regular message tape, and means under the control of said tape indicators for determining the sequence of transmission of all of said transmitters.

3. In a telegraph transmission station, a plurality of rush message transmitters, a tape indicator in each of said rush message transmitters, a stepping switch under the control of said tape indicators for determining the sequence of transmission of said rush message transmitters, a plurality of regular message transmitters, a tape indicator in each of said regular message transmitters, a stepping switch under the control of said latter tape indicators for determining the sequence of transmission of said regular message transmitters, and means controlled by said tape indicators and responsive to said stepping switches to give preference of transmission to said rush message transmitters.

4. In a telegraph transmission station, a plurality of rush message transmitters, a tape indicator in each of said rush message transmitters, a stepping switch under the control of said tape indicators for determining the sequence of transmission of said rush message transmitters, a plurality of regular message transmitters, a tape indicator in each of said regular message transmitters, a stepping switch under the control of said latter tape indicators for determining the sequence of transmission of said regular message transmitters, means controlled by said tape indicators and responsive to said stepping switches to give preference of transmission to said rush message transmitters, and means under the control of said latter tape indicators to preclude the operation of one of said rush message transmitters during the operation of one of said regular message transmitters.

5. In a telegraph transmission station, a plurality of priority message transmitters, a plurality of regular message transmitters, a numbering transmitter, means to cause operation of said numbering transmitter prior to the operation of any of said priority or regular message transmitters, means to cause operation of said priority message transmitters in preference to the operation of said regular message transmitters, means

15

associated with said regular message transmitters to preclude operation of said priority message transmitters during the operation of said regular message transmitters, and means under the control of said priority message transmitters to preclude operation of said regular message transmitters during the operation of said priority message transmitters.

6. In a transmission station, a first group of telegraph transmitters, a second group of telegraph transmitters, a stepping switch associated with each group of transmitters, said stepping switch controlling the selection of a transmitter from its respective group, means operating in accordance with the setting of said selector switches to cause the operation of said first group of telegraph transmitters in preference to the operation of said second group of telegraph transmitters, and means to insure the completion of transmission over any one of said transmitters of one group prior to the transmission of any one of said transmitters of the other group.

7. In a telegraph transmission station, a plurality of rush message transmitters, a tape indicator in each of said rush message transmitters, a stepping switch under the control of said tape indicators for determining the sequence of transmission of said rush message transmitters, a plurality of regular message transmitters, a tape indicator in each of said regular message transmitters, a stepping switch under the control of said latter tape indicators for determining the sequence of transmission of said regular message transmitters, means controlled by said tape indicators and responsive to said stepping switches to give preference of transmission to said rush message transmitters, a numbering transmitter, and means responsive to said stepping switches for causing operation of said numbering transmitter prior to the operation of any of said rush or regular message transmitters, whereby message identification may occur.

8. In a telegraph transmission station, a plurality of rush message transmitters, a tape indicator in each of said rush message transmitters, a stepping switch under the control of said tape indicators for determining the sequence of transmission of said rush message transmitters, a plurality of regular message transmitters, a tape indicator in each of said regular message transmitters, a stepping switch under the control of said latter tape indicators for determining the

16

sequence of transmission of said regular message transmitters, a numbering transmitter, means at said numbering transmitter responsive to an end-of-number signal, means responsive to said stepping switches for causing operation of said numbering transmitter prior to the operation of any of said rush or regular message transmitters, whereby message identification may occur, and means responsive to said end-of-number signal responsive means and said stepping switches and controlled by said tape indicators to give preference of transmission to said rush message transmitters.

9. In a telegraph transmission station, a plurality of rush message transmitters, a tape indicator in each of said rush message transmitters, a stepping switch under the control of said tape indicators for determining the sequence of transmission of said rush message transmitters, a plurality of regular message transmitters, a tape indicator in each of said regular message transmitters, a stepping switch under the control of said latter tape indicators for determining the sequence of transmission of said regular message transmitters, a numbering transmitter, means at said numbering transmitter responsive to an end-of-number signal, means responsive to said stepping switches for causing operation of said numbering transmitter prior to the operation of any of said rush or regular message transmitters, whereby message identification may occur, means responsive to said end-of-number signal responsive means and said stepping switches and controlled by said tape indicators to give preference of transmission to said rush message transmitters, and means controlled by said tape indicators and said end-of-number signal responsive means to preclude the operation of others of said transmitters during the operation of any one of said transmitters.
